TOY ROLLING HOOP

Wilton L. Turner, 619 S. Fayetteville St., and John Randolph Ingram, Oakmont Drive, both of Asheboro, N.C. 27203

Filed May 18, 1965, Ser. No. 85,336

Term of patent 14 years

(Cl. D34—15)

FIG. 1 is a perspective view of toy rolling hoop showing our new design; and

FIG. 2 is a vertical sectional view taken on the line 2—2 of FIG. 1.

The characteristic features of my design include a relatively wide flat rim and a flat disc encompassed thereby, said disc having an enlarged central opening and a plurality of radial slots formed therein, substantially as shown.

We claim:

The ornamental design for a toy rolling hoop, as shown and described.
